UNITED STATES PATENT OFFICE.

ALEC J. GERRARD AND PARVIN WRIGHT, OF CHICAGO, ILLINOIS.

WIRES-BUNDLING MACHINE.

Application filed June 12, 1923. Serial No. 568,303.

To all whom it may concern:

Be it known that we, ALEC J. GERRARD and PARVIN WRIGHT, respectively a subject of the King of Great Britain and a citizen of the United States, residing at Chicago, in the county of Cook and State of Illinois, have invented certain new and useful Improvements in Wire-Bundling Machines; and we do hereby declare the following to be a full, clear, and exact description of the invention, such as will enable others skilled in the art to which it appertains to make and use the same.

This invention relates to a wire tying machine especially adapted for bundling or securing any packages or shingles which have been dipped in hot tar, although it is also adapted for bundling other articles as well.

The object of the invention is to improve the devices heretofore proposed.

With this and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:

20 Figure 1 is a side elevational view of an apparatus made in accordance with this invention;

Figure 2 is a detail view of a portion of the parts shown in Figure 1, illustrating the machine in its inoperative position; and

Figure 3 is an end elevational view of the parts illustrated in Figure 1, showing duplicate arrangement of conveyors and machines.

40 1 indicates any suitable framework preferably of a pipe construction, having the vertical standard shown, and the overhead portion 2 on which is adjustably mounted the sleeves 3, having the depending support 4, and at the point 5 on each of said

45 supports is mounted a pair of lazy tongs 6 having the counterweighted ends 7 and from the lower point 8 of which is suspended as by the lug 9 a wire tying machine of the

50 well known construction shown. This wire tying machine, as is well known, is provided with a holding post 10, a wire twisting mechanism 11, a cutter and holding post 12,

55 a tensioning device 13, a lever 14 adapted to operate said tensioning device, and a lever

15 adapted to operate the wire twisting mechanism. Located between the vertical standards 1 of the framework is a suitable conveyer supporting framework 16, on which is mounted a pair of conveyors 17 and 18 of any suitable construction. In the form shown, these conveyors are provided with rollers, which are supported in the bracket members 19, and the conveyor flights or runways are separated by the vertical partition 20 preferably of metal. Said partition 20 is secured as at 21 to the sprocket chain 22, passing over the sprocket 23, mounted on the shaft 24, and adapted to be operated by the worm 25, rigid with the shaft 26 connected to the handle 27 and engaging the worm wheel 30 mounted on said shaft 24. There is preferably a pair of sprockets 28, one at each end of the shaft 24, and a pair of chains 22 also preferably employed.

By operating the handle 27, the central partition 20 may be readily raised and lowered, all as will be clear from the drawings.

35 represents a package or a bundle of hot shingles which have been previously dipped in tar, and therefore are very difficult to handle when placing wire ties or bands around the same, preparatory to shipment.

According to this invention; on the other hand, these said bundles 35 are placed on the conveyor 17, for example, jam up against the central partition 20, as best illustrated in Figure 3, and said conveyor 17 is made of such dimensions that the end of the bundle 35 will project over the edge of said conveyor, as illustrated. The shingles being thus brought into the position shown, the lazy tongs carrying the wire tying machine 40 are pulled down until the bottom 41 of said machine rests snugly on the top of the bundle 35. When the machine is brought to the position just described, one end of a tie wire 42 is secured in the holding post 10. The bight 43 is then carried first through the twisting mechanism 11, then through the second holding post 12, when said bight 43 is passed around the bundle and brought back and passed again through the holding post 10, the wire twisting mechanism 11, and the second holding post 12. Said wire is finally carried to the tensioning device 13 and secured therein, all in the manner

well known. The operator is enabled to readily thus entrain the wire around the bundle 35, although it is covered with tar, and is hot, and therefore difficult to handle, by reason of the fact that its projecting end 45 overhangs the edge bracket 19 of the conveyor 14. Further, since the lazy tongs 6 support the wire tying machine 40, the machine is readily brought to position and disposed of after the wire tying operation.

After the wire and machine are in the positions illustrated, the operator then reciprocates the wire tensioning handle 14, and places considerable tension on the wire, whereupon he seizes the handle or lever 15, and twists the two parallel bights of the wire which have entered the twisting mechanism, into a knot, in the manner well known, whereupon the machine automatically cuts off the bight or strand 43 and the end 45 of the bundle 35 is thus securely bound by a wire end portion and without the operator having been put to the necessity of touching with his hands the hot and sticky bundle at all.

After the end 45 of the bundle has been thus wired in the manner disclosed, the conveyor 17 readily moves the bundle to the end 46 of the partition 20. This conveyor 17 may be operated by any means not shown, or the operator may simply employ a stick to push the bundle to the end 46 of the partition 20. When the bundle has been thus brought to the end of the partition, it is shoved endwise from the conveyor 17 onto the conveyor 18 and into the position shown in Figure 3. When brought to its new position, its end 45 will be against the partition 20, and its end 48 will overhang the outer bracket 49, as illustrated. The operator next pulls down the second wire tying machine 50, which is supported by the lazy tongs 51, and the second wire 52 is secured in the binding post 10 of said second machine, it is carried through the twisting mechanism thereof through the second binding post, is entrained around the end 48 of the bundle 35, it is brought back to the first mentioned binding post 10, carried through the twisting mechanism, and through the second binding post, all as disclosed above, whereupon the parallel disposed bights of the wire are tensioned by operating the tensioning lever 14 of the second machine 50, and the parallel bights of the wire are twisted into a knot by operating the twisting lever 15, of said second machine, all in the manner above disclosed.

The surplus length of the wire is automatically cut off by the machine, and the bundle 35 is thus provided with a second wire on its other end, under tension, and securely tied in a knot, all as above disclosed.

It will thus be clear that with the apparatus above disclosed, and by manipulating

the same in the manner set forth, one is enabled to handle hot bundles of shingles or of other material, whether they be coated with tar or not, without touching the same, and he is enabled to provide both ends of said bundles with tie wires ready for shipment with great celerity and efficiency.

It is convenient to raise and lower the partition 20 for different heights of bundles, in that they can be manipulated more easily, when the partition does not extend too high above the top surfaces of the bundles being wired, and especially is it desirable and even necessary to lower said partition 20 when the bundles are so long that they will not rest upon the single conveyor 17. That is, in the case of very long bundles, it is necessary to lower the partition down below the surfaces of the conveyors 17 and 18 and permit the bundles to rest on both the conveyors 17 and 18, with their ends overhanging. On the other hand, when the bundles are short, as illustrated, it is very desirable to get the overhanging ends all in substantially the same plane, and by raising the partition to the position shown, one may take a stick or other instrument, and push all the ends of the shingles against said partition, and thus make a smooth and sightly bundle, all as will be readily apparent from the above disclosure.

It is obvious that those skilled in the art may vary the details of construction as well as the arrangement of parts without departing from the spirit of the invention, and therefore we do not wish to be limited to the above disclosure except as may be required by the claims.

What we claim is:

1. In a bundling machine for hot or sticky articles, the combination of a support beyond which said articles may project; a wire tying machine positioned above said support provided with means for holding and securing together two bights of a wire; and a vertically positioned partition against which the ends of said articles may be abutted, substantially as described.

2. In a bundling machine for hot or sticky articles, the combination of a support over which one end of said articles may project when bundled; a partition against which the other end of said articles may be abutted to properly position the same in the bundle; a second support above said first named support; and means for adjustably suspending a wire tying machine from said second support, substantially as described.

3. In a bundling machine for hot or sticky articles, the combination of a support beyond which said articles may project; a wire tying machine positioned above said support provided with means for holding and securing together two bights of a wire; a vertically positioned partition against which

the ends of said articles may be abutted; and means for raising and lowering said partition, substantially as described.

4. In a bundling machine for hot or sticky articles, the combination of a support over which one end of said articles may project when bundled; a partition against which the other end of said articles may be abutted to properly position the same in the bundle; a second support above said first named support; and means comprising a pair of lazy-tongs for adjustably suspending a wire tying machine from said second support, substantially as described.

5. In a bundling machine for hot or sticky articles, the combination of a support beyond which said articles may project; a wire tying machine positioned above said support provided with means for holding and securing together two bights of a wire; a vertically positioned partition against which the ends of said articles may be abutted; a second support over the edge of which said articles may also project; and a second wire tying machine positioned above said second support; substantially as described.

6. In a bundling machine the combination of a pair of supports over which may project the ends of articles to be bundled; a vertically adjustable partition separating said supports; and a pair of wire tying machines positioned above said supports adapted to apply wires to the projecting ends of said articles, substantially as described.

7. In a bundling machine the combination of a pair of supports comprising conveyor members over which may project the ends of articles to be bundled; a vertically adjustable partition of a length less than that of said supports separating said supports; and a pair of wire tying machines positioned above said supports adapted to apply wires to the projecting ends of said articles, substantially as described.

8. In a bundling machine the combination of a pair of supports over which may project the ends of articles to be bundled; a vertically adjustable partition separating said supports; a pair of wire tying machines positioned above said supports adapted to apply wires to the projecting ends of said articles; and a pair of lazy-tongs for adjusting the positions of said wire tying machines, substantially as described.

9. In a bundling machine the combination of a pair of bench like supports provided with rollers; an adjustable vertically disposed partition located between said supports and of a length less than said supports; means for raising and lowering said partition between said supports; and a pair of wire tying machines adjustably supported above said supports, substantially as described.

In testimony whereof we affix our signatures.

ALEC J. GERRARD.
PARVIN WRIGHT.
